UNITED STATES PATENT OFFICE.

LOUIS WILLIAMS MCKEEHAN, OF ORANGE, NEW JERSEY, AND WILLIAM EARL PATRICK, JR., OF BOISE, IDAHO, ASSIGNORS TO GOVERNMENT OF THE UNITED STATES.

SUBMARINE MINE.

Application filed October 19, 1922. Serial No. 595,673.

To all whom it may concern:

Be it known that we, LOUIS WILLIAMS MCKEEHAN and WILLIAM EARL PATRICK, Jr., citizens of the United States, residing at Orange, New Jersey, and Boise, Idaho, respectively, have invented new and useful Improvements in Submarine Mines, of which the following is a specification.

This invention relates to improvements in submarine mines and more particularly to means for closing the circuit of electrically fired means on contact with a passing ship.

One of the objects of the present invention is to provide an inexpensive, reliable and efficient circuit closure for submarine mines which may be installed on mine cases now in general use without material alteration.

A further object is to provide a member adapted to be attached to the exterior of a mine casing for engagement by a passing ship and on such engagement to complete a circuit and fire the mine.

A further object is to provide a device of the last above mentioned character which may be inexpensively manufactured, assembled and installed.

Other objects will be in part obvious and in part hereinafter pointed out in connection with the accompanying sheet of drawings illustrating in cross section one of various possible modifications.

Referring to this drawing in detail, 1 denotes a section of an ordinary spherical mine case now in general use which is provided with one or more central openings in each of which is fitted a plug 2 preferably of copper but suitably insulated from the mine casing by means of insulation washers 3 and 4. This plug 2 has a recess 5 tapped out on its upper side and a similar recess 6 on its lower side within the mine casing.

Engaging the upper recess is a central stud 7 preferably integrally formed with a contact member 8 adapted to be engaged by a passing ship and separated from the part 7 by a restricted portion 10 permitting the end 8 to be easily broken off under certain conditions or be bent on engagement with a ship to carry a disc 11 into engagement with a stiff annular member 12 surrounding but out of contact with the disc 8. The part 7 is suitably insulated from the member 12 by insulation blocks 13 and 14 simi-

lar to the parts 3 and 4. A bushing 15 is interposed between the central stud 7 and the insulating bushing 13, to prevent abrading of insulating washer 13 when central stud 7 is being screwed into position. A polygonal shoulder 16, integral with central stud 7, is adapted to be engaged with a suitable wrench. Thus a rigid assembly is obtained. Likewise, a nut 17 holds the disc 11 in place against a shoulder 18.

The lower recess 6 is engaged by a binding post stud 20 provided with a clamping or lock nut 21. Lock nuts 22 also are provided on the under side of the plug 2 for the purpose of securing the insulated bushings 3 and 4 in water tight relation to the casing 1 and plug 2.

There is shown diagrammatically in the lower right hand corner of the figure the wiring circuit which includes one part 23 grounded on the mine casing at 24 at one side of a low voltage battery 25 while at the opposite side of the battery the lead 26 includes the detonator 27 and is secured to the binding post 20. Using a battery of this type, no appreciable current can pass through sea water before metallic contact is established between the central part and a relatively large steel surface. It will thus be seen that when the circuit is closed current will flow from the battery through the mine casing to the member 12 thence to the disc 11 through the stud 7 and plug 2 to the binding post 20 through the detonator and thence to the opposite side of the battery.

It is believed that it is unnecessary to describe the operation and use of the present invention further than above set forth, as the mechanism will be clear to those skilled in the art. The device is of simple and practical construction, reliable and efficient in use and operation, inexpensive to manufacture and well adapted to accomplish all of the objects and advantages herein set forth.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and, therefore, such adaptations should

and are intended to be comprehended within the meaning and range of equivalency of the following claims.

What we claim is:—

- 5 1. In a submarine mine, in combination, a casing, a contact member mounted thereon, a projection carried by the mine and insulated therefrom adapted to be engaged by a passing ship and bent into engagement with said first mentioned member thereby to electrically complete a circuit and fire the mine.
- 10 2. In a submarine mine, in combination, a mine casing, an annular member mounted thereon adapted to be connected with one side of a battery, a projection centrally disposed within said member and electrically connected through a detonator to the opposite side of said battery, said central member being insulated from said annular member but adapted to be bent into engagement therewith when engaged by a passing ship.
- 15 3. In a submarine mine, in combination, a mine casing, an annular contact member mounted thereon and in electrical engagement therewith, said mine casing having an opening, a closing plug mounted therein, a contact device carried by said closing plug adapted to be bent to engage said annular

member when engaged by a passing ship, a circuit including a battery and a detonator, the wires of said circuit being connected respectively to said central member and said annular member, whereby the circuit is completed and the mine fired when the central member and the annular member are moved into contact.

30 35 4. In a submarine mine, in combination, a mine casing having an opening, a closing plug mounted therein but insulated from said casing, a battery in said casing, an annular member associated with the closing plug but insulated therefrom, a central contact member mounted on said plug and surrounded by said annular member, said casing and contact member being connected to the opposite leads from said battery, and a detonator in circuit therewith adapted to be fired when the circuit is closed by the engagement of said contact member with the 40 45 50 annular member.

Signed at New York, N. Y., this 10th day of July, 1922.

LOUIS WILLIAMS McKEEHAN.

Signed at Washington, D. C., this 4th day of August, 1922.

WILLIAM EARL PATRICK, JR.
